UNITED STATES PATENT OFFICE.

DAVID WILLIAM BROOKS, OF ROYSTON, GEORGIA.

STERILIZER.

1,133,088.

Specification of Letters Patent. Patented Mar. 23, 1915.

Application filed April 29, 1914. Serial No. 835,158.

To all whom it may concern:

Be it known that I, DAVID W. BROOKS, a citizen of the United States, and a resident of Royston, in the county of Franklin and State of Georgia, have made certain new and useful Improvements in Sterilizers, of which the following is a specification.

My invention is an improvement in sterilizers, and has for its object to provide a device of the character specified, adapted for the simultaneous sterilization of a number of articles, as for instance drinking glasses for soda fountains, schools and other public places, wherein the articles are simultaneously washed or cleansed by boiling water, and at the same time sterilized by steam, and wherein the articles are so arranged during the cleansing, that the contents may easily escape from the glass, and wherein the bases of the articles are thoroughly protected from breakage due to expansion and contraction.

In the drawings: Figure 1 is a front view of the improved sterilizer, with the doors open, Fig. 2 is a longitudinal vertical section, and Fig. 3 is a section on the line 3—3 of Fig. 1, with the doors closed.

The present embodiment of the invention comprises a cabinet 1 divided by a partition to be described into two compartments 2 and 2^a, and the front of the cabinet is open and may be closed by means of doors 3 and 3^a. The partition before mentioned consists of a double wall, the walls 4 and 4^a being spaced apart from each other, and at the front the partitions are connected by a vertical facing 5, against which the doors 3 and 3^a will close. The doors are hinged at 6 to the opposite sides of the casing, and close toward each other.

The space within the partition is in effect a conduit, extending through the top and the bottom of the casing, as indicated at 7 and 8, and at the top of the casing the end 7 of the conduit is inclosed by a hood 9 from which leads a pipe 10. The compartment 2^a is divided by a horizontal partition 11 into a small upper compartment and a large lower compartment, and the compartment 2 is divided into three compartments by transverse partitions 12. Each of the partitions 12 is chambered or hollow, being in fact a lateral extension of the conduit 13 between the partition walls 4 and 4^a, and each of the said extensions is closed at its outer end, as shown in Fig. 2.

A tray 14 is seated on the upper face of each of the partitions 12, and on the bottom of the compartment 2, each tray being designed to receive the articles 15 to be washed and sterilized. A boiler 16 of suitable capacity and strength is arranged within the compartment 2^a above the partition 11, and a gas burner or other heater 17 is arranged below the boiler just above the partition, and in position to heat the contents of the boiler.

A water gage 18 is arranged outside the casing at the compartment 2^a, and is connected to the boiler by upper and lower pipes 19 and 19^a respectively, the gage being at the side of the casing remote from the compartment 2. A pressure gage 20 is arranged above the casing, at the compartment 2^a, and is connected to the boiler by a pipe 21, and pipes 22 and 22^a lead from the end of the boiler adjacent to the conduit 13, the said pipes extending into the conduit.

The pipe 22 extends downward in the conduit to the bottom thereof, and branches 23 lead from the said pipe into the partition 12, and into the hollow or chambered bottom 12^a of the casing. At spaced intervals each of the branches 23 is provided with a transverse pipe 24, the said transverse pipes 24 communicating with the pipe 23 intermediate their ends, and each of the cross pipes 24 is provided with a series of upwardly extending nipples or discharge tubes 25, the said tubes passing through the upper walls 9 of the partitions 12, and through the upper wall of the chambered bottom 12^a, and each tube also extends through the bottom of the adjacent tray.

The trays 14 are of a size in the present instance to receive sixteen glasses, and each glass is arranged in inverted position on the tray, with its open end resting on the tray, and with the adjacent discharge tube 25 at the center of the open end. The pipe 22 leads from the boiler above the water level, so that steam will be discharged through the pipe 22, and through the pipe 23 and its transverse branches 24, and through the discharge nipples 25 into the interior of the glass or other article to be cleansed.

The pipe 22^a extends upward and downward in the conduit, and at each of the partitions 12 the said pipe is provided with a branch 26. The top of the casing at the compartment 2 is also hollow or chambered, as shown at 12^b, and one of the branches 26

from the pipe 22^a extends into the interior or chambered portion of the top. Each of the branches 26 of the pipe 22^a is provided with cross or transverse pipes 27 at spaced intervals, and at each discharge nipple 25 each of the transverse pipes 23 is provided with a downwardly extending discharge tube or nipple 28.

It will be evident that when a glass is arranged on the tray over a discharge tube 25, it will be beneath a discharge tube 28 of the pipe 22^a, and the pipe 22^a leads from the boiler below the water level, so that the nipples or tubes 28 discharge water onto the glasses. A hood 29 is provided for each article, the hood fitting the bottom or lower end of the glass, and each hood is provided with a reduced portion 30, which extends through an opening in a plate 31. With each plate 31 there is connected a hood 29 for each article, and each hood and reduced portion 30 is provided with an opening 32 extending from the upper end of the reduced portion to the interior of the hood.

The opening 32 of each hood is engaged by the adjacent discharge tube or nipple of the water supply pipe, and the said tubes or nipples fit loose enough in the openings to permit the plates 31 to be raised and lowered. The plates 31 are spaced apart from each other at regular intervals, and each plate is connected to the next upper plate by means of four flexible members 33, the said members being of cord or wire.

The uppermost plate 31 has connected with each corner a flexible member 33^a, similar to the members 33, and the said flexible members pass upwardly over pulleys 34 journaled at the top of the casing, and outwardly to a connection at 35 with the adjacent door 3. The arrangement is such that when the door is opened, all of the plates and all of the hoods will be simultaneously lifted, as indicated in Fig. 1, while when the door is closed all of the plates 31 and the hoods 29 will be lowered.

The trays 14 may be removed, since the trays are not connected in any manner to the partitions 12 or to the bottom 12^a, or to the discharge tubes 25. Each tray is provided with openings for receiving the said tubes 25, so that the tray may be seated on the partition or on the bottom, the discharge tube passing upward through the opening. In that part of the compartment 2^a below the partition 11, guides 36 are provided, for receiving the trays 14.

The operation of the device is as follows: The glasses to be washed and sterilized may be first properly placed on the trays, each glass being placed over an opening. The trays are then placed in the compartment 2, with the discharge tubes 25 passing upwardly through the openings of the tray, as shown in Fig. 2. When the door 3 is closed,

the hoods will be lowered onto the glasses, and the sterilizer is now ready for operation. The steam generated in the boiler passes through the pipe 22, and is discharged through the tubes 25 into the interior of the glasses, thoroughly cleansing and sterilizing the same. The boiling water passes out from the pipe 22^a, and is discharged from the pipes 28 on to the glasses, striking the bottoms first, and then running down the sides of the glasses. After the glasses have been thoroughly cleansed, they may be removed in the trays from the compartment 2, and inserted in the compartment 2^a, the trays resting on the guides 36.

With a sterilizer of the size shown, forty-eight glasses may be simultaneously washed and sterilized. It will be obvious, however, that the number of articles sterilized at one time will depend upon the size of the sterilizer. It will be noted from an inspection of Fig. 2, that the top of the casing at the compartment 2^a is provided with an opening 37 leading into the hood 9, and the chambered top 12^a of the casing is provided with a similar opening 38 at the hood, both walls of the said top being perforated. The extension 7 of the conduit 13 also opens into the hood. Thus all of the waste steam and the products of combustion from the heater may pass out at the hood.

The extension 8 at the bottom of the conduit permits the air to enter to provide for a circulation of air through the conduit, to remove the products of combustion and the waste steam. The gage 20 always indicates the pressure in the boiler, and the water gage indicates the height of water. It will be noticed that the pipe 19 opens above the water level while the pipe 19^a opens below the same.

In use, the glasses are first thoroughly cleansed by the boiling water, discharging through the pipes 26 and 28, thus thoroughly cleansing the glasses. After they have been thoroughly cleansed they may be sterilized by the steam and the hoods 29—30 protect the glasses against breakage.

Suitable valves 40 and 41 are provided for regulating the flow of water and steam from the boiler to the articles, the former being placed in the hot water pipe 22^a, and the latter in the steam pipe 22. The valve 40 is for the purpose of admitting and shutting off the flow of water to the branch pipes 26, while the valve 41 is for the purpose of controlling the flow of steam from the boiler to the discharge nozzles 25. The boiler is provided with the usual filling opening 42, for the purpose of permitting the same to be filled with water.

I claim:

1. A sterilizer for drinking glasses and like articles, comprising a cabinet or casing having an open front, and a door for clos-

ing the front, the top and the bottom of the casing being chambered, and said casing having chambered partition walls arranged horizontally and separating the interior of the casing into compartments, trays for holding the glasses or other articles seated on the bottom and the partitions, a boiler having a steam pipe provided with branches extending through the upper walls of the bottom and of the partitions and through the trays to discharge into the articles on the trays, said boiler having a hot water pipe leading into the partitions and the top of the casing, and provided with branches 10 discharging downwardly through the lower walls of the partitions and the top and in register with the first-named branches, said trays being removable, a hood in connection with each of the last-named branches 15 and slidably connected with the branch for protecting the bottoms of the glasses when in inverted position on the trays, a common support for the hoods in each compartment of the casing, a connection between the supports, and a connection between the uppermost support and the door for lowering the supports when the door is closed and for raising the supports when the door is opened, said casing having a lateral compartment 20 for the boiler, and the said lateral compartment having guides for receiving the trays after the glasses have been cleaned.

2. A sterilizer for drinking glasses and like articles, comprising a cabinet or casing having an open front, and a door for closing the front, the top and the bottom of the casing being chambered, and said casing having chambered partition walls arranged horizontally and separating the interior of the casing into compartments, trays for holding the glasses or other articles seated on the bottom and the partitions, a boiler having a steam pipe provided with branches 25 extending through the upper walls of the bottom and of the partitions and through the trays to discharge into the articles on the trays, said boiler having a hot water pipe leading into the partitions and the top of the casings and provided with branches discharging downwardly through the lower walls of the partitions and the top and in register with the first-named branches, said trays being removable, a hood in connection with each of the last-named branches and slidably connected with the branch for protecting the bottoms of the glasses when 30 in inverted position on the trays, a common support for the hoods in each compartment of the casing, and a connection between the supports and the door for simultaneously raising and lowering the supports when the door is open and closed.

4. A sterilizer for drinking glasses and like articles, comprising a cabinet or casing having an open front, and a door for closing the front, the top and the bottom of the casing being chambered, and said casing having chambered partition walls arranged horizontally and separating the interior of the casing into compartments, trays for holding the glasses or other articles seated on the bottom and the partitions, a boiler having a steam pipe provided with branches 35 extending through the upper walls of the bottom and of the partitions and through the trays to discharge into the articles on the trays, said boiler having a hot water pipe leading into the partitions and the top of the casings and provided with branches discharging downwardly through the lower walls of the partitions and the top and in register with the first-named branches, said trays being removable, and a hood in connection with each of the last-named branches and slidably connected with the branch for protecting the bottoms of the glasses when 40 in inverted position on the trays.

5. A sterilizer for drinking glasses and like articles, comprising a cabinet or casing having an open front, and a door for closing the front, the top and the bottom of the casing being chambered, and said casing having chambered partition walls arranged horizontally and separating the interior of the casing into compartments, trays for holding the glasses or other articles seated on the bottom and the partitions, a boiler 45 having a steam pipe provided with branches discharging downwardly through the lower walls of the partitions and the top and in register with the first-named branches, said trays being removable, and a hood in connection with each of the last-named branches and slidably connected with the branch for protecting the bottoms of the glasses when 50 in inverted position on the trays.

6. 3. A sterilizer for drinking glasses and

extending through the upper walls of the bottom and of the partitions and through the trays to discharge into the articles on the trays, said boiler having a hot water pipe leading into the partitions and the top of the casings and provided with branches discharging downwardly through the lower walls of the partitions and the top and in register with the first-named branches, said trays being removable.

6. A sterilizer comprising a cabinet or casing and having compartments arranged one above the other, trays for holding the articles arranged in the compartments and removable therefrom, a boiler having a hot water pipe provided with branches discharging downwardly on to the individual articles in the trays, and having a steam pipe discharging upwardly through the trays and in register with the steam pipe branches, hoods for protecting the bottoms of the articles when in inverted position on the

trays, said hoods being slidable with respect to the steam pipe branches and the said branches discharging through the hoods, a support for the hoods of each compartment, and means for simultaneously lifting and lowering the supports.

7. A sterilizer comprising a cabinet or casing and having compartments arranged one above the other, trays for holding the articles arranged in the compartments and removable therefrom, a boiler having a hot water pipe provided with branches discharging downwardly on to the individual articles in the trays, and having a steam pipe discharging upwardly through the trays and in register with the water pipe branches.
